[57] **CLAIM**

The ornamental design for a bathtub, as shown and described.

DESCRIPTION

FIG. 1 is a perspective view taken from the top, front and right side of a tub showing our new design;

FIG. 2 is a top plan view thereof;

FIG. 3 is a cross-sectional view taken on line 3—3 of FIG. 2;

FIG. 4 is a cross-sectional view taken on line 4—4 of FIG. 2; and,

FIG. 5 is an enlarged cross-sectional view taken on line 5—5 of FIG. 2.

The fragmentary line representations of a mounting area in FIG. 1 and of dotted line holes shown in FIGS. 1 and 2 are for the purpose of illustration only, and form no part of the claimed design.

FIG. 1

FIG. 5

FIG. 3

FIG. 4
